UNITED STATES PATENT OFFICE

1,979,266

MINING MACHINE

Morris P. Holmes, Claremont, N. H., assignor to
 Sullivan Machinery Company, a corporation of
 Massachusetts

Application July 6, 1922, Serial No. 573,149
 Renewed November 29, 1930

152 Claims. (Cl. 262—28)

My invention relates to mining machines.

An object of my invention is to provide an improved mining machine. Another object of my invention is to provide an improved mining machine having improved propulsion mechanism. A further object of my invention is to provide an improved mining machine having improved adjusting means for the cutting mechanism. A still further object of my invention is to provide an improved mining machine having cutting mechanism mounted in an improved manner whereby the same may be adjusted to insert a kerf in practically any plane in advance of the machine within the operating limits of the machine. Other objects and advantages of my invention will hereinafter more fully appear.

In the accompanying drawings I have shown for purposes of illustration one form which my invention may assume in practice.

In these drawings,—

Fig. 1 is a side elevation of a mining machine constructed in accordance with the illustrative form of my invention, the bar being partially broken away and shown in undercutting position.

Fig. 2 is a plan view of such a machine.

Fig. 3 is a sectional view, partially in elevation, on the broken section line 3—3 of Fig. 4, the bar being shown in shearing position.

Fig. 3a is a detail view showing a portion of the control mechanism.

Fig. 4 is a vertical section, partially in elevation, on the broken section line 4—4 of Fig. 3, the bar being shown in shearing position.

Fig. 4a is a detail showing an interlock for the controls.

Fig. 5 is a horizontal section on the line 5—5 of Fig. 4.

Fig. 6 is a vertical section on the section line 6—6 of Fig. 3.

Fig. 7 is a vertical section on the section line 7—7 of Fig. 4.

Fig. 8 is a detail showing locking mechanism.

Fig. 9 is a section on the broken line 9—9 of Fig. 8.

Fig. 10 is a view, partially in elevation and partially in section on an enlarged scale, of truck frame tilting means of an improved construction employed in the illustrative form of my invention.

Fig. 11 is a vertical section on the broken section line 11—11 of Fig. 10.

Fig. 12 is a vertical section on the line 12—12 of Fig. 2.

Fig. 13 is a vertical section on the section line 13—13 of Figs. 1 and 4.

Fig. 14 is a vertical section on the section line 14—14 of Fig. 2.

Fig. 15 is a diagrammatic view showing various positions in which the cutter bar may be disposed.

Figs. 16, 17, 18, 19, 20 and 21 are various simplified views showing different cuts by the machine.

Referring first to Figures 1 and 2, the apparatus as a whole comprises a truck consisting of a truck body 1 mounted on wheels 2 and adapted to run upon a track 3 upon which truck is mounted a mining mechanism generally designated M, and including a motor casing 4, a gear housing 5, a cutter bar 6 and supporting and adjusting mechanism for the cutter bar generally designated 7, which mechanism I shall hereafter more fully describe.

For the purpose of permitting a moderate angular adjustment of the mining machine M as a whole about a transverse horizontal axis, there is provided the following mechanism: Secured to angle irons 8 forming the upper lateral portions of the truck body 1 are circular members 9 bolted as at 10 to the members 8 and forming pivots about which the mining machine is tiltable. It will be noted that these members are located about midway between the axles of the truck. The machine frame is provided at its opposite sides with projecting bearing members 12 bolted as at 13 to the sides of the machine about midway of the length of the gear casing 5, which members 12 have curved bearing surfaces 14 which pivotally support the mining machine as a whole upon the members 9.

It will also be observed that the members 12 are arranged about at the center of mass of the tilting machine frame, and accordingly that no great amount of force is necessary to enable the tilting of the machine about its pivot. For the purpose of effecting this tilting, there is disposed upon the truck frame 1, in suitable journals 15, a transverse rock shaft 16 to which at opposite sides of the center thereof but closely adjacent to each other there are secured a pair of similar arms 17 which are connected at their free ends by a bolt 18 upon which there are rotatably mounted in a suitable manner rollers 19. These rollers are arranged in guideways 20 which are secured to the bottom of the machine M itself. It will be observed from Fig. 10 that when the machine frame is in a horizontal position, the arms 17 are not vertical and

60

70

75

80

85

90

95

100

105

110

so that upon swinging of the shaft 16 and resultant swinging of the arms 17, the rollers 19 traveling within the slots 20 will cause a tilting movement of the machine frame as a whole.

5 This tilting may be in either direction about the transverse pivot. In order to lock the shaft 16, an arm 21 is secured by keying or any other suitable manner to one end thereof and with this arm there cooperates arm swinging 10 means comprising an arm engaging member 22, which is threaded throughout a considerable portion of its length as indicated at 23, supported in suitable horizontal guides 24 and moved longitudinally upon rotation of the nut 25 engaging the threaded portion 23, which nut may be rotated upon the member 23 by a hand operated ratchet and pawl mechanism 26. It will be observed that, depending upon the direction in which the nut 25 is turned, the arm 20 21 and so the arms 17 will be swung in opposite directions and the machine frame will either be tilted from horizontal or brought back to horizontal position, it being further observed that the guides 24 are integrally connected to 25 the truck frame and so that as tilting of the frame occurs and as movement of the arm 21 takes place, there will be no binding at the connection between the member 22 and the arm 21.

30 Within the motor casing 4, there is arranged a motor (not shown) supplied with current through a usual reeling device 4' described in a previously filed application, the motor herein being reversible and provided with suitable controlling and reversing mechanism of any suitable or usual construction. The motor comprises an armature shaft 30 which projects through opposite ends of the motor casing 4 and operates to supply power for the driving of 35 the cutting mechanism, the shifting thereof, and the feeding movements of the machine as a whole both during cutting and in running around the mine. The rear end of the armature shaft which is designated 31 carries thereon 40 a spur pinion 32 which meshes with a spur gear 33 keyed or otherwise suitably secured to a horizontal longitudinally extending shaft 34 upon which a worm 35 is arranged. The worm meshes with a worm wheel 36 mounted upon a 45 transverse hollow shaft 37 and by means of a suitable friction control 38, which is of a well known construction, a driving sprocket 39 whose position is shown in Figs. 1 and 2 may be reversibly driven, depending upon the direction 50 of rotation of the shaft 30; or at the will of an operator upon suitable manipulation of the friction mechanism 38 be permitted to rotate when disconnected from the shaft 37. At its opposite end, the armature shaft 30 is extended, 55 as later described, and carries near the motor casing 4 a spur pinion 40 which meshes with and drives a spur gear 41 arranged upon a horizontal longitudinally disposed shaft 42, supported in suitable bearings 43 within the gear housing 5. At its forward end, the shaft 42 carries a bevel pinion 44 which is disposed between and drives a pair of bevel gears 46 and 47. The latter are connectable by friction clutch mechanisms of a well known form, and which 60 are generally designated 48 and 49, alternately with a transverse horizontal shaft 50. A suitable shipper mechanism 51 carried by a hollow horizontal transverse sleeve 52 is normally held in neutral position by oppositely acting springs 53 arranged between adjustable collars 54 and 65 collars 55 engaging the ends of the sleeve 52. Within the sleeve 52 is a shaft 56 having shoulders 57 adapted to engage the collars 55 and to free the sleeve of the influence of one or the other of the springs 53. The shaft 56 is movable by the coaction of a rack 58 and gear segment 59 in a manner to effect control of the clutches 48 and 49 and so the alternate connection or the complete disconnection of the gears 46 and 47 from the shaft 50. The segment 59 is controlled by a hand lever 60 upon the top 70 of the gear housing 5, which lever has a neutral and two operating positions in which it may be locked by any suitable means. It will be observed that the loading of the friction clutches is by the springs 53 and these may be adjusted to cause slipping of the frictions at any desired load, so as to prevent overloading the motor. The shaft 50 is provided with a worm 61 which meshes with a worm wheel 61' upon a collar 62 which is keyed to a horizontal longitudinally extending shaft 63 arranged below and to one side of the shaft 42. It will therefore be obvious that reverse rotation of the shaft 63 is effected by reverse rotation of the 75 shaft 50. The shaft 63 is supported in suitable bearings 64 and 65 formed in the gear casing 5 and the shaft carries adjacent the former of these bearings and to the rear of the worm wheel 61', a worm 67 which meshes with and drives a worm wheel 68 rotatably mounted on a transverse horizontal shaft 69 journaled as at 70 in the gear casing 5. The shaft 69 has keyed thereto a sleeve 71 upon which spur teeth 72 are formed. A similar spur gear 73 is operatively connected to the worm gear 68 and a sliding clutch sleeve 74 movable by a shipper 75 is adapted to connect the pinion 72 with the pinion 73 for simultaneous rotation, and so driving of the shaft 69 may be effected. The 80 shaft 69 has a portion 76 projecting through the side wall of the gear casing 5 and carries keyed thereon a driving sprocket 77. The clutch shipper 75 is arranged upon a shaft 78 which projects through the top of the gear casing 100 and is operable by a handle 79 which may be locked in its operating positions by any suitable means.

The truck wheels 2 are mounted on axles 80 which extend completely across the truck body 105 1. The rear axle 80 is provided with a pair of sprocket wheels numbered respectively 81 and 82, the wheel 81 being arranged at that side of the truck body at which the sprockets 77 and 39 are to be found. The forward axle 110 80 has secured thereto a sprocket wheel 83, and a chain 84, cooperating with the sprockets 82 and 83, connects the axles for simultaneous rotation in the same direction. A driving chain 115 85 passes, as best shown by dotted chain lines 120 in Fig. 1, around the sprockets 39 and 77 and around the sprocket 81 upon the rear axle 80, it being also observed from Fig. 1 that the chain passes around a further sprocket 86 which, as best shown in Fig. 12, is adjustable in position 125 to vary the tension of the chain. The adjusting mechanism for the sprocket 86 is as follows: The sprocket 86 is mounted upon a shouldered sleeve 87 which cooperates with a circular member 88 having a flange 89 in clamping a stationary circular seat 90 carried upon the frame of the mining machine. A stud 91 is threaded into the member 88 and a nut 92 is adapted to connect rigidly a chain guard 93, the member 87, the members 88 and 90 in 130

- such manner as to hold the sprocket in any desired position. As it will be noted that the portion of the member 87 about which the sprocket 86 is rotatable is not concentric with the portion of the member 87 which is rotatable in the journal on the main frame, it will be evident that the member 87 may so move as to provide more slack or to tighten the chain 85 and then securely hold it in desired position.
- 10 A similarly adjustable sprocket 94 is arranged between the truck wheels 2 and serves both as a means for additional chain tightening and to keep the chain off the track.
- Having described thus far the mechanism 15 which is used for effecting translational movements of the machine, I will describe its operation. It will be evident that during running around the mine it is immaterial so far as this operation is concerned whether the cutter chain 20 runs at all or what direction it runs in, although it is preferable that it does not run at all, as is the case herein. It is accordingly possible to reverse the motor and so to reverse the direction of rotation of the armature shaft 30 without 25 out in any way interfering with the operation of the mechanism. Accordingly, the friction clutch mechanism 38 will suffice to control the connection of the rear end of the armature shaft 30 with 31 by way of the pinion 32, gear 33, worm 35, 30 worm wheel 36, and shaft 37 with the driving sprocket 39 and so effect the running of the machine at a relatively high rate of speed about the mine. When it is desired to cut and feed the machine during cutting, it is obvious 35 that unless the cutter bits are to be shifted the motor must run in one direction. Accordingly, it must be possible, if sumping and withdrawing cuts are to be used, to reverse the direction of movement of the machine without reversing 40 the motor. For this reason I have provided the reversible driving mechanism including the clutches 48 and 49, etc. and so am able to reverse the direction of rotation of the driving sprocket 77 at will while maintaining the 45 direction of rotation of the armature shaft 30 unchanged. Let it be assumed that it is desired to effect bodily movement of the machine in one direction, then to maintain it stationary, and then to move it bodily in the opposite direction.
- 50 Under these circumstances, whichever one of the friction clutches 48 or 49 as should be operated to effect the proper drive of the sprocket 77 for forward feed will be engaged. Thereupon the shaft 50 will rotate the worm 55 61, the latter will drive the worm wheel 61', the shaft 63, the worm 67 and the worm wheel 68, and, if the clutch member 74 is in proper position to connect the gears 72 and 73, the shaft 69 will be rotated and so the sprocket 77 will be rotated to effect forward feed. It 60 will be evident, by reason of the presence of the several worms and other reducing elements in this train, that the speed during cutting will be much less than that during running around the mine, and it will be obvious that during the 65 rotation of the sprocket 77 by power, the friction clutch 38 will be so operated as to allow the idle rotation of the sprocket 39. When the machine has been fed in a forward direction as far as desired, the handle 60 will be swung in such way as to cause disconnection of both the friction clutches 48 and 49 and the machine will be then locked in its position upon the track as the worms will prevent rotation of the 70 truck axles. All that is necessary to effect 75
- retraction of the machine is to throw in the other of the clutch members 48 and 49 and the machine will then be retracted in the desired manner. During running around the mine, it will be evident that by placing the clutch 80 shipper 51 in mid-position, the mechanism for driving the shaft 69 may be rendered inoperative, but it will be necessary on account of the presence of the worms to throw the clutch member 74 to a position to disconnect the spur teeth 72 and 73, and then the shaft 69 and sprocket 77 will be rotated idly during the movement of the machine about the mine.
- It will be observed that the armature shaft 30 at its forward end extends completely across the full length of the gear housing 5 and is journaled in the front end of that housing in a bearing member 95 in which suitable anti-friction bearing means 95' are arranged. The extreme forward end of the shaft 30 carries suitably keyed, or otherwise held thereon, a spur driving pinion 96 whose connections with other portions of the mechanism will be hereinafter described. The front end of the gear casing 5 herein also terminates in a flange 100 95 to which there is secured by bolts 101 a collar member 102 having an inwardly directed rim 103 at the forward side thereof. The rim 103 constitutes retaining means for an annular internal gear member 104 which is journaled in the member 102 and to a flange 105 on which there is bolted as at 106 a member 107 which may be referred to as a neck or turret member. The member 107 has an annular recess 108 formed therein overlying the flange or rim 103. 100 The member 107 at a point spaced longitudinally of the machine from the portion thereof which is bolted to the internal gear 104 and in eccentric relation to the latter is provided with a circumferential rim or flange 109 to which 105 an internal gear member 110 is bolted as at 111. This internal gear member partially overlies an annular groove 112 in the flange 109 and thereby serves to lock in position a sleeve-like member 113 which has a rim or flange 114 110 inwardly directed and disposed in the recess 112. To the member 113 is bolted as at 115 a second turret member 116 which supports the cutter mechanism and forms a casing for the bar swinging and cutter chain driving mechanism. It will be observed that the turret member 107 is rotatable upon rotation of the internal gear 104 about a longitudinally extending horizontal axis which coincides with the axis of the armature shaft 30, while it will be observed 120 from Fig. 3 that the turret member 116, while rotatable about a horizontal axis, is not rotatable about an axis coincident with the axis of the armature shaft 30, but about a parallel axis offset therefrom a material distance.
- Extending midway between the sides of the turret member 116 and journaled in suitable bearings 117 is a shaft 118 about whose axis the turret member 116 is rotatable. The shaft 118 carries suitably secured to the rear end 140 thereof a spur gear 119 which is constantly in mesh with the spur gear 96 and which is driven thereby. At its forward end the shaft 118 carries a beveled pinion 120. This pinion meshes with a beveled gear 121 which is secured to a 145 sleeve 122 within which a shaft member 123 is arranged, this shaft member being provided between its ends with a spur gear 124 and at its top having fixed thereto in any suitable manner a cutter chain driving sprocket 125. The shaft 150

123 at its lower end is journaled in a suitable bearing 126 which is supported in a plate member 127 secured to the lower side of the sleeve 122. The member 127 is journaled in turn in a bearing 128 suitably supported in a web 129 forming a portion of the turret 116. Arranged coaxially with the shaft 123 is a beveled driving pinion 130 which is held in constant driving relationship with the gear 121 by an interlocking connection 131 through the intermediation of the sleeve 122 and plate member 127.

Upon one side of the turret member 116 there is arranged what might be termed a third turret member 135 to which the cutter bar 136 carrying the cutter chain 136' is secured by bolts 137. The turret member 135 is bolted as at 138 to a large internal gear 139 which is journaled in a sleeve-like flange member 140 bolted as at 141 to the front of the turret member 116 and provided with an inwardly directed flange 142 to hold the internal gear member 139 in place. It will be observed that the turret member 135 is traversed by an opening 143 in which suitable roller bearings or other antifriction means 144 are interposed between the member 135 and the shaft 123. The turret castings 116 have a flange 146 which supports the gear 139 at the side opposite the flange on the member 140. At this point, it may be noted that in the form of my invention shown herein the turret member 116 is made in two lateral halves for purposes of convenience of casting or assembly, but this particular type of construction is obviously not essential.

Disposed on opposite sides of the driving pinion 130 are a pair of bevel gears 150 and 151 which may be connected by suitable friction clutch mechanisms 150' and 151' of any well known type, herein of the multiple disc type, in driving relation with members 152 and 153 secured to a shaft 154 extending across the turret 116 perpendicularly to the direction of the shaft 123. The controlling mechanism for these clutches is identical in principle and mode of operation with that for the clutches 43 and 49, the similar parts being designated by primed numbers. The shaft 154 is journaled at its opposite ends in suitable anti-friction bearings 155 carried on the turret member 116 and has keyed to it adjacent the opposite ends thereof, a pair of worms 156 and 157. These worms mesh respectively with worm wheels 158 and 159. The latter are rotatable on axes parallel to the axis of the shaft 123. The axes of rotation of the gears 158 and 159 lie in a vertical plane transverse to the longitudinal axis of the armature shaft. As in their general construction the mountings for the gears 158 and 159 are similar, with the exception of the fact that the gear 159 has additional connections not present in the case of the gear 158, it will be sufficient to describe the arrangement of the gear 159. This gear is journaled in a bearing 160 in the side of the turret 116 opposite the cutter bar, the gear being secured in any suitable way, (herein bolted on) to the hollow shaft 161 which is journaled in the bearing 160. At its upper end the hollow shaft 161 is connected to a sleeve 162 whose periphery is provided with gear teeth 163 upon which is slidable a toothed clutch member 164. Coaxial with the sleeve 161 is a shaft 165 which is arranged within the hollow shaft 161 and journaled at its upper end in an anti-friction bearing 167 carried by the turret 116. Between the anti-friction bearing and the member 162

the shaft 165 is provided with a toothed portion 168 which may be connected with the teeth 163 by the clutch element 164. It will thus be evident that by properly shifting the clutch member 164, the worm wheel 159 may be connected with the gear 163. It will be observed that the teeth of the member 168 are relatively long and this construction is employed in view of the fact that the member 168 is in constant mesh with a gear 170 keyed to a hollow shaft 171 and journaled in anti-friction bearings 172 on an axis parallel to the axes of rotation of the worm wheels 158 and 159 and herein equi-distant from said axes. The connection for and mounting of the wheel 158 is substantially identical with the details of the mounting for the wheel 159 as so far described and by operating a clutch member corresponding to the clutch member 164 the wheel 158 may be caused to drive the gear 170.

In order that the gear 170 may not be simultaneously connected with the wheels 158 and 159, I employ the following mechanism for shifting the clutch members 164. Extending transversely across the front end of the turret 116 is a shaft 173, which shaft is journaled for rotation on an axis parallel to the plane which includes the axes of rotation of the wheels 158 and 159. Arranged coaxial with the shaft 173 are a pair of sleeve members 174 and 175, which sleeve members carry at their adjacent ends mutilated pinions 176 and 177 respectively, which pinions mesh with short racks 178 and 179, these racks being pivotally connected to rocker arms 180 and 181 which carry the shipper forks 182 and 183 for shifting the clutch members 164 and are pivoted on the turret 116. For the purpose of operating the sleeves 174 and 175, I have provided suitable mechanism which will prevent the engagement of one of the clutch mechanisms except at a time when the other is out. This mechanism is interchangeable from one side to the other of the turret for convenience in handling the machine and includes a pair of handles 184 and 185. The handle 184 may be connected directly to either end of the shaft 173, while the handle 185 may be connected directly to either of the sleeves 174 or 175. For the purpose of connecting the shaft 173 with the other of the sleeves, I employ a member 186 which is adapted to be secured to either end of the shaft 173 and which fits over and may be connected by a suitable spline, or in any other manner, to the sleeve 174 or 175 to which the handle 185 is not then connected. It will thus be evident that the two handles may be placed at the same side of the turret and yet operate both of the clutches as desired. For the purpose of preventing the engagement of one clutch when the other is engaged, or in fact in any position except full disengagement, I arrange a plate 188 between the handles 184 and 185 and can secure this plate by screws 189 at either side of the turret depending upon the positions of the handles. The plate is traversed by an opening 190 through which there is slidably arranged a round or cone-ended locking pin 191. These pin receiving sockets are respectively numbered, for the handles 184 and 185, 194 and 195. The length of the pin 191 is such that, when one end of the same is received in either of the sockets 194 or 195, the handle in which the end of the pin is not received can be turned, but the length is such that, until the pin can be forced out of the socket which it then

80

85

115

120

125

130

135

140

145

150

occupies, the handle containing that socket cannot be turned, it being understood that the handles are provided with abutment surfaces adjacent the sockets to prevent the movement of the pin out of the socket in which it may be lodged except at the time when the other socket comes opposite the pin. From this description, it will be gathered that the sockets are so placed in the handles 184 and 185 that, when both sockets are in clutch disconnecting position, the sockets 194 and 195 come over the pin 191. Accordingly, as soon as either of the handles is moved, the pin 191 is forced into one of the sockets in such manner as to lock that lever which has not been moved and until the lever which has been moved is returned to initial or off position the other lever is held against movement.

20 The worms 156 and 157 are of materially different pitch, the purpose of this being to provide for different rates of swing of the cutter bar. The shaft 171 upon which the gear 170 is keyed is provided at its upper end with a driving pinion 200, which pinion meshes with the internal gear 25 139. As a result, it will be observed that the turret 135 may be turned to swing the cutter bar about the axis of the shaft 123 by rotation of the gear 170 and, since the gear 170 is arranged to be rotated in opposite directions and at different speeds by the connections previously described, it will be understood that the bar may be swung in opposite directions and at different speeds at the will of the operator. The swing 30 of the bar that is accomplished by the drive from the worm 157 is employed for positioning the bar prior to cutting, while the worm 156 is used to swing the bar during the making of a swinging cut. No means is needed to lock the bar during the time when it is not to be swung 35 40 as, so long as either of the clutches 164 is in clutch engaging position, there can be no movement of the bar on account of the presence of the worms in the drive connections for the gear 200.

200.
45. Now returning for a moment to the description of the mechanism driven by the worm gear 159 and noting Fig. 7, it will be seen that between the members 161 and 162 there is secured the supporting flange of a bevel gear 201. This bevel gear is accordingly rotated whenever the worm wheel 159 is rotated. The gear 201 meshes with another bevel gear 202 secured to a hollow shaft 203 journaled upon an axis parallel to the axis of the shaft 118 in the turret 116. This hollow shaft at its rear end carries a spur pinion clutch element 204. Coaxial with the shaft 203 and journaled at one end within the bore of that shaft is a shaft 205, which shaft is provided near one end with spur teeth 206 corresponding to the spur teeth 204 and connectable with the latter by a shiftable clutch element 207 which may be moved by a rocker shaft 208 and clutch shipper lever 209 engaging the groove 210 in the periphery of the member 207, there being a suitable operating handle 211 arranged upon the end of the shaft 208 where the latter projects through the wall of the turret casing 116. Upon the opposite end of the shaft 205 there is a pinion 212 which meshes as indicated in Fig. 4 with the internal gear 110. It will therefore be clear that if desired, by connecting the elements 204 and 206 by means of the element 207 and by the driving of the worm 157 it will be possible to cause rotation of the turret 116 about the axis of the shaft 118 since, the internal gear 110 being se-

cured to the inner periphery of the front end of the turret member 107, the turret member 116 will be rotated as the shaft 205 travels in a circle around the axis of the shaft 118. To prevent rotation of the turret 107 about the axis of the shaft 30 except at desired times, I employ a suitable locking means best shown in Figs. 8 and 9 comprising a number of rack teeth 213 mounted upon an arm 214 and swinging about a shaft 215 which projects through the wall of the gear casing 5 in such manner as to be accessible for the attachment thereto of an operating lever 217. This operating lever may be fixed in locking or unlocking position by the aid of suitable gear teeth 219 and latch 220. Similar locking means is employed in conjunction with gear 110, the parts controlling locking of the turret 116 being similarly controllable, the difference being that in the first case the gear is held stationary by the locking means, while in the other the gear is already stationary and the turret 116 is the part held.

Formed upon the shaft 63 forwardly of the bearing 65 is a spur clutch element 221 which is connectable with a similar clutch element 222 secured to a shaft 223 which is journaled at one end within the shaft 63 and at its opposite end in the front plate of the gear housing 5 as at 224. The shaft 223 has formed upon it a pinion 225 which meshes with the internal gear 104. A suitable clutch element or sleeve 226 is arranged to interconnect the clutch elements 221 and 222 and may be shifted by the shipper element 227 controlled by a handle 228 at the top of the gear housing 5, the handle 228 serving to rotate the shaft 229 which swings the shipper element 227 and is locked in its operative position by any suitable means. It will be evident that depending upon the direction of rotation of the reversible rotatable shaft 63 the turret 102 may be turned in opposite directions, while the same may be prevented from turning during cutting feed of the machine by simply disconnecting the clutch elements 221 and 222.

The possibility of disconnecting the shaft 123 from the sleeve 122 for the purpose of interrupting chain drive is obvious from what has gone before. For the purpose of accomplishing this, a sleeve 230 is slidably disposed adjacent the top of the sleeve 122 and by means of teeth 231 secured to the sleeve 122, upon suitable shifting of the element 230 upwardly, the teeth 124 and the teeth 231 may be connected to cause driving of the cutter chain driving sprocket 125 while, by downward movement of the sleeve or clutch element 230, drive of the cutter chain driving sprocket 125 may be interrupted. The member 230 is provided in its periphery with an annular groove 236 with which a shipper element 237 cooperates. This element is moved by a lever 238 keyed on the shaft 239, the lever 238 being one arm of a bell crank 240. The other arm 241 of the bell crank is slotted as at 242 and an eccentric pin 243 mounted upon a transverse shaft 244 projecting through the side of the turret 116 and provided with an operating lever 245 serves to permit the shifting of the bell crank lever in a manner to connect or disconnect the cutter chain drive.

Before beginning a description of the mode of operation of my machine as a whole, it should be noted that the relationship of the driving elements for the spur gear 225 and the relative number of teeth on that gear and upon the internal gear 104 are such that, as the entire turret 150

116 is bodily rotated about the axis of the armature shaft, the cutter bar may be maintained in any given plane it happens to be in at the beginning of such bodily rotation, for the gearing 5 which rotates the turret 116 on the axis of the shaft 118 is so proportioned that the turret 116 will rotate on its own axis at such a rate as to keep the plane of the bar constantly parallel to a given plane. This phenomenon is accomplished 10 by simultaneously releasing both turrets 107 and 116. It will be understood that it is not necessary to accomplish this result for, by employing the drive for the gear 225 while the drive for the gear 212 is interrupted, there will be no 15 turning of the turret 216 about the axis of the shaft 118, and if the gear 212 is driven while the gear 225 is not driven, there will be no bodily rotation of the turret 116, although the same will rotate about the axis of the shaft 118. 20 Figure 15 is presented for the purpose of showing the different possibilities of cut with my improved mining machine. For the purpose of more readily considering this figure and certain details of operation which I shall now 25 give, let the axis of rotation of the armature shaft 30 be designated A. A will then be the axis about which the turret 116 is bodily rotatable and in which the turret 107 turns. Let the axis of the shaft 118 be designated B. B is 30 then the axis about which the turret 116 turns. Let the axis of the shaft 123 be designated C. C is the axis about which the cutter bar swings. Now observing Figure 15, it will be noted that the axis A is, except for tilting slightly above 35 and below a horizontal position, fixed save for longitudinal movement in the direction of bodily movement of the entire machine. The axis B is rotatable about the axis A in the path designated D and shown in a dot-and-dash line in 40 Fig. 15. The cutter bar which is offset from the axis B may be caused to assume any position around the axis B irrespective of the position of the axis B, the several paths passed through by the cutter bar in different illustrative positions being indicated by the circles E, F, G and H. Dependent upon the relative amount of offset between the axes A and B and the distance of the cutter bar from the axis B, it will be 45 possible to obtain varying results in the limits 50 in which the machine may cut. If the distance between the central plane of the cutter bar and the axis B is equal to or less than the distance between the axes A and B, conceived of as extended in parallelism with each other, it will 55 be possible for the cutter bar to be brought into a plane which coincides with its plane and which passes through the axis A. If the distance between the axis B and the plane of the bar is greater than the distance between the axis B 60 and the axis A, the cutter bar can never assume a position in the plane which includes the axis A. If a cutter chain of sufficient width of cut is employed, it will be evident from the outer series of bar positions indicated at I₁, I₂, . . . I₈, 65 that they may be made to cut in a complete cylindrical path. The positions of the bar shown at J' and J² demonstrate the possibility of moving the bar into positions in the same plane with the bar supporting elements in different relative 70 positions.

To make plain the mode of operation of this mechanism its operation as a whole will be concisely explained. On entering the mine, the machine will run to the room in which work is 75 to be done under power transmitted to the truck

wheels 2 from the armature shaft 30 by way of the pinion 32, gear 33, worm 35, wheels 36, driving sprocket 39 and the sprocket chain 85. When the machine reaches the place where a cut is to be made, the bar may be adjusted into any desired plane by effecting rotation about one or both of the axes A and B, as may be found necessary. The bar may be swung about the axis C by the fast swinging means described as a preliminary to a sumping cut. The entire machine may be fed into the coal by means of the truck drive effected by driving sprocket 77. When the cut has been made to the desired depth, rotation of the driving sprocket 77 may be discontinued and the machine will be locked in position owing to the worms in the sprocket drive. The mechanism for swinging the bar may then be employed to swing the bar during the making of a transverse cut, at this time the slow swinging feed previously described being employed. When the bar has made its swinging cut by reversing the drive of the sprocket 77, the machine may be backed out of the coal, completing the cut during the retraction. The parts may be then operated to bring the longitudinal axis of the cutter bar into parallelism with the longitudinal axis of the machine and the bar brought down to a position near the track where the equilibrium will be more stable. The machine may then be run off to a new place 105 where work is to be done. For longwall cutting all that is necessary to do is to swing the bar at right angles to the longitudinal axis of the machine. Longwall cuts as well as shortwall cuts may be made at any height and further 110 may be made at any angle within a very wide range. If it is desired to make an undercut, or a top cut at a slight angle, this can be accomplished by providing the bar with a slight initial 115 downward or upward tilt by tilting the entire 115 machine around the transverse axis extended by the journal members 9. It will be equally clear that when desired any variety of shearing, either adjacent the center of the room or entry, or adjacent the side wall, within reasonable 120 limits as to width, may be made with my improved mechanism, there being no useful type 125 of cut of which I am now aware which cannot be produced by my machine as herein illustrated or when modified in an obvious manner. The views contained in Figs. 16 to 21 show certain possibilities, but there are obviously others which will suggest themselves to those skilled in the art.

While I have in this application specifically described one form which my invention may assume in practice, it will be understood that this form of the same is shown for purposes of illustration and that the invention may be modified and embodied in other forms without departing from its spirit or the scope of the 135 appended claims.

What I claim as new and desire to secure by Letters Patent is:

1. In a mining machine, a portable frame, 140 cutting means thereon including a motor mounted on said frame, and means driven from the opposite ends of said motor shaft for respectively effecting feed of said frame as a whole during cutting and feed during running around a 145 mine.

2. In a mining machine, running gear, a motor supported on said running gear, and means for effecting drive of said running gear including a single driving connecting with said run- 150

- ning gear alternatively driven by opposite ends of said motor.
3. In a mining machine, a portable frame, cutting mechanism mounted thereon, a motor mounted on said frame having a power shaft and adapted to actuate said cutting mechanism, and self-contained means driven from the opposite ends of said power shaft for effecting translation of said frame at different predetermined speeds while said motor speed remains substantially constant.
4. In a mining machine, a portable frame, cutting mechanism mounted thereon, a motor mounted on said frame having a power shaft and adapted to actuate said cutting mechanism, and means driven from the opposite ends of said motor shaft for respectively effecting feed of said frame during cutting and feed during running around a mine.
5. In a mining machine, a portable frame, cutting mechanism mounted thereon, a motor mounted on said frame having a power shaft extending longitudinally of said frame and adapted to actuate said cutting mechanism, and means driven from the opposite ends of said power shaft for effecting translation of said frame at different speeds including clutch means for rendering said feeds alternately operative.
6. In a mining machine, a portable frame, cutting mechanism mounted thereon, a motor mounted on said frame having a power shaft extending longitudinally of said frame and adapted to actuate said cutting mechanism, and means driven from the opposite ends of said motor shaft for respectively effecting feed during cutting and feed during running around a mine.
7. In a mining machine, running gear, a reversible motor mounted on said running gear, and means alternatively driven by opposite ends of the motor shaft for effecting drive of said running gear, said means driven by one end of said motor shaft including gearing for effecting reverse drive of the running gear without reversal of the motor.
8. In a mining machine, running gear, a reversible motor mounted on said running gear, and means alternatively driven by opposite ends of the motor shaft for effecting drive of said running gear, said means driven by one end of said motor shaft including means for effecting reverse drive of the running gear without reversal of the motor and each of said means being frictionally controlled.
9. In a mining machine, running gear including a rotatable propelling member engaging the surface over which said machine moves, a motor supported on said running gear, and driving means therefor including a single driving element rotatable coaxially with said propelling member alternatively driven by opposite ends of the motor to effect drive of said member, said driving means being frictionally controlled during either drive.
10. In a mining machine, running gear, a motor supported on said running gear, and means including a single driving connection with said running gear and alternatively operative clutches for driving said running gear in either direction by either end of the motor shaft.
11. In a mining machine, running gear, a reversible motor supported on said running gear, and means including a single driving connection to said running gear alternatively driven in either direction by either end of the motor shaft for actuating said running gear, said means in- cluding mechanism whereby said running gear may be driven in opposite directions by one end of said motor shaft without reversal of the motor, and said mechanism being included only in the connections between one end of said motor and said single driving connection.
12. In a mining machine, running gear, a reversible motor supported on said running gear, and means including a single driving connection to said running gear alternatively driven in either direction by either end of the motor shaft for actuating said running gear, said means including mechanism whereby said running gear may be driven in opposite directions by one end, but only one end, of said motor shaft without reversal of the motor, and said mechanism being included only in the connections between one end of said motor and said single driving connection.
13. In a mining machine, running gear, a motor mounted on said running gear, said running gear including a shaft on which a driving member is mounted, and means for driving said driving member including separate driving elements each constantly operatively connected with said driving member and respectively adapted to be driven in either direction by opposite ends of the motor shaft.
14. In a mining machine, a truck frame, means for effecting translation thereof including a truck wheel, a rotatable driving member for said truck wheel, a plurality of rotatable elements constantly connected for rotation with said rotatable driving member and adapted selectively to constitute driving members for the latter, driving means for said rotatable elements, and mechanism between said driving means and said elements operative to connect them in driven relation to said driving means or to permit free rotation thereof.
15. In a mining machine, a truck frame, means for effecting translation thereof including a truck wheel, a driving sprocket connected with said wheel in driving relation, a chain passing around said sprocket, a pair of driving sprockets operatively engaging with said chain, and means whereby either of said last mentioned sprockets may be driven by power or permitted to rotate idly.
16. In a mining machine, a truck frame, means for effecting translation thereof including a truck wheel, a driving sprocket connected with said wheel in driving relation, a chain passing around said sprocket, a pair of driving sprockets operatively engaging with said chain, and means whereby either of said last mentioned sprockets may be driven in either direction by power or permitted to rotate idly.
17. In a mining machine, a truck frame, means for effecting translation thereof including a truck wheel, a driving sprocket connected with said wheel in driving relation, a chain passing around said sprocket, a pair of driving sprockets operatively engaging with said chain, and means whereby either of said last mentioned sprockets may be driven at different rotative speeds by power or permitted to rotate idly.
18. In a mining machine, a truck frame, means for effecting translation thereof including a truck wheel, a driving sprocket connected with said wheel in driving relation, a chain passing around said sprocket, a pair of driving sprockets operatively engaging with said chain, and means whereby either of said last mentioned sprockets

- may be driven at different speeds in either direction by power or permitted to rotate idly.
19. In a mining machine, a truck frame, means for effecting translation thereof including a truck wheel, a driving sprocket connected with said wheel in driving relation, a chain passing around said sprocket, a pair of driving sprockets operatively engaging with said chain, and means including a single motor disposed on said truck frame whereby either of said last mentioned sprockets may be driven by power or permitted to rotate idly.
20. In a mining machine, a truck frame, means for effecting translation thereof including a truck wheel, a driving sprocket connected with said wheel in driving relation, a chain passing around said sprocket, a pair of driving sprockets operatively engaging with said chain, and means including a single motor disposed on said truck frame whereby either of said last mentioned sprockets may be driven by power or permitted to rotate idly, said last mentioned means including means for rotating one of said last mentioned sprockets in opposite directions while said motor rotates in the same direction.
21. In a mining machine, a truck and driving means therefor including a member having rotary motion only relative to said truck and operative on rotation to effect movement of translation of the truck, a plurality of toothed members constantly operatively connected through their peripheries with said first mentioned member, a motor, and means for connecting said motor selectively to either of said last mentioned members.
22. In a mining machine, a truck and driving means therefor including a member operative on rotation to effect movement of translation of the truck, a plurality of members constantly operatively connected with said first mentioned member and adapted alternatively to act as driving means therefor, a motor, and means for connecting said motor alternately to either of said last mentioned members, said last mentioned means including mechanism operative to drive one of said members in opposite directions without reversal of the motor.
23. In a mining machine, a truck and driving means therefor including a member operative on rotation to effect movement of translation of the truck, a plurality of members rotatable on parallel axes and constantly operatively connected with said first mentioned member, a reversible motor, and means for connecting said motor selectively to either of said last mentioned members.
24. In a mining machine, a truck and driving means therefor including a member operative on rotation to effect translation of the truck, a plurality of members rotatable on parallel axes and continuously connected in operative relation to said first mentioned member, a motor carried on said truck, and means including a reversing gearing and motor reversing means for effecting the driving in opposite directions of said first mentioned member.
25. In a mining machine, the combination with a cutter bar and driving motor therefor, of means for swinging said cutter bar in opposite directions at different speeds by power including a rotatable member to which said bar is connected, and means including parallel shafts perpendicular to the plane of swing of said bar selectively operable to drive said rotatable member to effect bar swing.
26. In a mining machine, the combination with a cutter bar and a driving motor therefor, of means for swinging said cutter bar in opposite directions at different speeds by power from said motor including a rotatable member by which said bar is carried, a driving member for said rotatable member rotating on an axis parallel to the axis of the latter, and driving means for said driving member including a plurality of driving trains each of which includes a shaft driven by said motor, said shafts being parallel to each other and to a plane including the axis of said driving motor.
27. In a mining machine, the combination with a cutter bar and a driving motor therefor, of means for swinging said cutter bar in opposite directions at different speeds by power including a rotatable member to which said bar is connected, and means including parallel shafts rotating at different speeds operatively connectible in driving relation with said rotatable member to swing said bar at different speeds.
28. In a mining machine, the combination with a cutter bar and a driving motor therefor, of means for swinging said cutter bar in opposite directions at different speeds by power from said motor including a rotatable member by which said bar is carried, a driving member for said rotatable member rotating on an axis parallel to the axis of the latter, and a pair of shafts driven by said motor at different speeds and disposed parallel to said axis of rotation and operatively connectible with said driving member.
29. In a mining machine, the combination with a cutter bar and a driving motor therefor, of means for swinging said cutter bar in opposite directions at different speeds by power from said motor including a rotatable member by which said bar is carried, a driving member for said rotatable member rotating on an axis parallel to the axis of the latter, a pair of shafts driven by said motor at different speeds and disposed parallel to said axis of rotation and operatively connectible with said driving member, and means manually operable to effect such connection alternately but not simultaneously.
30. In a mining machine, the combination with a cutter bar and a driving motor therefor, of means for swinging said cutter bar in opposite directions at different speeds by power from said motor including a rotatable member by which said bar is carried, a driving member for said rotatable member rotating on an axis parallel to the axis of the latter, a pair of shafts driven by said motor at different speeds and disposed parallel to said axis of rotation and operatively connectible with said driving member, and means manually operable to effect such connection alternately but not simultaneously, said means being provided with operating elements adapted to be arranged at either side of said cutter bar.
31. In a mining machine, the combination with a cutter bar and a driving motor therefor, of means for supporting and positioning said bar to cut in various planes parallel to a horizontal axis and for swinging said bar during cutting including a turret rotatable on a horizontal axis and means carried by said turret including a rotatable member to which said bar is connected and means including parallel shafts rotating at different speeds each operatively connectible in driving relation with said rotatable member.
32. In a mining machine, the combination with a cutter bar and a driving motor therefor,

- of means for supporting and positioning said bar to cut in various planes parallel to a horizontal axis and for swinging said bar during cutting including a turret rotatable on a horizontal axis 5 and means carried by said turret including a rotatable member by which said bar is carried, a driving member for said rotatable member rotating on an axis parallel to the axis of the latter, and a pair of shafts driven by said motor 10 and disposed parallel to said axis of rotation and each operatively connectible with said driving member.
33. In a mining machine, the combination with a cutter bar and a driving motor therefor, of means for supporting and positioning said bar to cut in various planes parallel to a horizontal axis and for swinging said bar during cutting including a turret rotatable on a horizontal axis and means carried by said turret including a rotatable member by which said bar is carried, a driving member for said rotatable member rotating on an axis parallel to the axis of the latter, a pair of shafts driven by said motor and disposed parallel to said axis of rotation and each 20 operatively connectible with said driving member, and means manually operable to effect such connection alternately but not simultaneously.
34. In a mining machine, the combination with a cutter bar and a driving motor therefor, of means for supporting and positioning said bar to cut in various planes parallel to a horizontal axis and for swinging said bar during cutting including a turret rotatable on a horizontal axis and means carried by said turret including a rotatable member by which said bar is carried, a driving member for said rotatable member rotating on an axis parallel to the axis of the latter, a pair of shafts driven by said motor and disposed parallel to said axis of rotation and each 25 operatively connectible with said driving member, and means manually operable to effect such connection alternately but not simultaneously.
35. In a mining machine, the combination with a cutter bar and a driving motor therefor, of means for supporting and positioning said bar to cut in various planes parallel to a horizontal axis and for swinging said bar during cutting including a turret rotatable on a horizontal axis and means carried by said turret including a rotatable member by which said bar is carried, a driving member for said rotatable member rotating on an axis parallel to the axis of the latter, a pair of shafts driven by said motor and disposed parallel to said axis of rotation and each 30 operatively connectible with said driving member, and means manually operable to effect such connection alternately but not simultaneously, said means being provided with operating elements adapted to be arranged at either side of said cutter bar.
36. In a mining machine, the combination with a machine frame, a pivoted cutter, and a driving motor therefor, of means for supporting said cutter on said frame permitting angular adjustment thereof about an axis extending longitudinally of said frame, said cutter being adapted to cut in planes parallel to the axis of said adjustment and being adjustable by power from said motor towards and from said axis and being swingable automatically at different rates in opposite directions about its pivot.
37. In a mining machine, the combination with a pivoted cutter and a driving motor therefor, of means for supporting the cutter including a turret rotatable about a substantially horizontal axis, said cutter being disposable successively in parallel planes differently spaced from said axis and being swingable by said motor in opposite directions in any of said planes at different speeds while said motor speed remains constant, and motor operated devices for effecting disposition of said cutter bar toward and from said axis into said parallel planes at a bar positioning speed.
38. In a mining machine, a machine frame, a pivoted cutter bar, and means for adjusting said cutter bar and supporting the same on said frame including a plurality of turrets rotatable on parallel horizontal axes, and a plurality of turret rotating shafts offset from but parallel to said axes.
39. In a mining machine, a machine frame, a pivoted cutter bar, and means for adjusting said cutter bar and supporting the same on said frame including a plurality of turrets rotatable on parallel horizontal axes, and a plurality of turret rotating shafts offset from but parallel to said axes, the shaft for rotating one of said turrets being carried on said frame and the shaft for rotating the other turret being carried by the latter.
40. In a mining machine, a machine frame, a pivoted cutter bar, and means for adjusting said cutter bar and supporting the same on said frame including a plurality of turrets rotatable on parallel horizontal axes, and a plurality of turret rotating shafts offset from but parallel to said axes, the shaft for rotating one of said turrets being carried on said frame and the shaft for rotating the other turret being carried by the latter.
41. In a mining machine, a machine frame, a pivoted cutter bar, and means for adjusting said cutter bar and supporting the same on said frame including a plurality of turrets rotatable on parallel horizontal axes, and a plurality of turret rotating shafts offset from but parallel to said axes, the shaft for rotating one of said turrets being carried on said frame and the shaft for rotating the other turret being carried by the latter.
42. In a mining machine, a machine frame, a pivoted cutter bar, and means for adjusting said cutter bar and supporting the same on said frame including a plurality of turrets rotatable on parallel horizontal axes, and a plurality of turret rotating shafts offset from but parallel to said axes, the shaft for rotating one of said turrets being carried on said frame and the shaft for rotating the other turret being carried by the latter.
43. In a mining machine, a machine frame, a pivoted cutter bar supported thereon for swinging in different angularly related planes, a motor on said frame, and means for swinging said bar by power from said motor including bar swinging mechanism and a friction clutch between elements of said mechanism having automatically limited loading means, said loading means including a spring normally tending to load said clutch.
44. In a mining machine, a machine frame, a pivoted cutter bar supported thereon, a motor on said frame, and means for swinging said bar by power from said motor including bar swinging mechanism between certain of whose elements a friction clutch is arranged, said clutch having a spring normally tending to load the same and manual means for permitting said spring so to operate without applying additional force thereto.

45. In a mining machine, transmission mechanism, a friction clutch, a shipper therefor movable to load the same, a spring tending to move said shipper to load said clutch, means normally preventing said spring from moving said shipper to load said clutch, and manually movable means operable to permit said spring to cause loading of said clutch without applying additional force thereto.
- 10 46. In a mining machine, transmission mechanism, a friction clutch operable when loaded to cause driving of said transmission mechanism in one direction, a friction clutch operable when loaded to cause driving of said transmission mechanism in the other direction, a shipper intermediate said clutches, a pair of springs tending to move said shipper in opposite directions, and manual means for rendering one of said springs inoperative to permit the other to cause loading of one of said frictions, said last mentioned spring acting expansively against a fixed abutment to effect loading.
- 15 47. In a mining machine, transmission mechanism, a friction clutch operable when loaded to cause driving of said transmission mechanism in one direction, a friction clutch operable when loaded to cause driving of said transmission mechanism in the other direction, a shipper intermediate said clutches, a pair of springs tending to move said shipper in opposite directions, manual means for rendering one of said springs inoperative to permit the other to cause loading of one of said frictions, said last mentioned spring acting expansively against a fixed abutment to effect loading and means for varying the compression of said springs.
- 20 48. In a mining apparatus, a wheel mounted truck, a mining machine on said truck, a chain drive for said truck including a chain loop operatively connected with at least one truck wheel, and a plurality of driving sprockets projecting laterally from said machine and engaging with said loop.
- 25 49. In a mining apparatus, a wheel mounted truck, a mining machine on said truck, a chain drive for said truck including a chain loop operatively connected with at least one truck wheel, a plurality of driving sprockets projecting laterally from said machine and engaging with said loop, and means for tightening or loosening said chain.
- 30 50. In a mining apparatus, a wheel mounted truck, a mining machine on said truck, a chain drive for said truck including a chain loop operatively connected with at least one truck wheel, a plurality of driving sprockets projecting laterally from said machine and engaging with said loop, and means for tightening or loosening said chain including an idler having an eccentric journal on its mounting.
- 35 51. In a mining apparatus, a truck, a mining machine thereon, said mining machine comprising a body and a plane pivoted cutter bar adjustable bodily about a pair of parallel pivots extending longitudinally of said body and also mounted for swinging movement in its own plane, and means for tilting said body on said truck to give said bar an upward or downward inclination.
- 40 52. In a mining apparatus, a machine frame, a turret rotatable about a horizontal axis supported on said frame, a cutter bar pivoted between its ends and mounted on said turret and swingable about an axis perpendicular to said horizontal axis, and means for swinging said
- 5 53. In a mining apparatus, a machine frame, a turret rotatable about a horizontal axis supported on said frame, a pivoted cutter bar mounted on said turret and swingable about an axis perpendicular to said horizontal axis, means for swinging said bar in opposite directions including a pair of members rotatable on axes perpendicular to the axis of swing of said bar and respectively at opposite sides of such axis.
- 80 54. In a mining apparatus, a machine frame, a turret rotatable about a horizontal axis supported on said frame, a pivoted cutter bar mounted on said turret and swingable about an axis perpendicular to said horizontal axis, means for swinging said bar in opposite directions including a pair of members rotatable on axes perpendicular to the axis of swing of said bar and respectively at opposite sides of such axis, and a pair of members rotatable on axes parallel to such axis.
- 85 55. In a mining apparatus, a machine frame, a turret rotatable about a horizontal axis supported on said frame, a pivoted cutter bar mounted on said turret and swingable about an axis perpendicular to said horizontal axis, means for swinging said bar in opposite directions including a pair of members rotatable on axes perpendicular to the axis of swing of said bar and respectively at opposite sides of such axis, a pair of members rotatable on axes parallel to such axis, and a member operative on rotation to directly effect swing of said bar, said last mentioned member being alternately connectible with said last preceding pair of members.
- 90 56. In a mining apparatus, a truck frame, a mining machine pivotally supported on said truck, and means for tilting said machine upon said frame and holding it without manual intervention in different adjusted positions including a horizontal shaft parallel to the axis of tilting and mounted on said frame, lever means secured to said shaft engaging the mining machine and connected thereto, and lever means on said shaft for turning the same.
- 95 57. In a mining apparatus, a truck frame, a mining machine pivotally supported on said truck, and means for tilting said machine upon said frame and holding it without manual intervention in a plurality of tilted positions including a horizontal shaft parallel to the axis of tilting and mounted on said frame, lever means secured to said shaft engaging and mining machine and connected thereto, and parallel lever means on said shaft for turning the same.
- 100 58. In a mining apparatus, a truck frame, a mining machine pivotally supported on said truck, and means for tilting said machine upon said frame including a horizontal shaft parallel to the axis of tilting and mounted on said frame, lever means secured to said shaft, means in fixed relation to said mining machine providing a slot in which the extremity of said lever means moves, and lever means on said shaft for turning the same.
- 105 59. In a mining apparatus, a truck frame, a mining machine pivotally supported on said truck, and means for tilting said machine upon said frame, lever means secured to said shaft engaging the mining machine, lever means on said shaft for turning the same, and means carried on said machine for applying force to said last mentioned lever means.
- 110 60. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 115 61. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 120 62. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 125 63. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 130 64. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 135 65. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.
- 140 66. In a mining apparatus, a truck frame, a mining machine pivotally supported on said truck, and means for tilting said machine upon said frame, lever means secured to said shaft, means in fixed relation to said mining machine providing a slot in which the extremity of said lever means moves, and lever means on said shaft for turning the same.

- 5 said frame including a horizontal shaft parallel to the axis of tilting mounted on said frame, lever means secured to said shaft engaging the mining machine, a lever on said shaft for turning the same, and means carried on said machine for applying force to said lever, said last mentioned means comprising a screw operatively connected to said lever and a manually rotatable nut carried by said machine.
- 10 69. In a mining apparatus, a truck frame, a mining machine pivotally supported on said truck, and means for tilting said machine upon said frame including a horizontal shaft parallel to the axis of tilting mounted on said frame, lever means secured to said shaft engaging the mining machine, a lever on said shaft for turning the same, and means carried on said machine for applying force to said lever, said last mentioned means comprising a screw operatively connected to said lever, a manually rotatable nut carried by said machine and ratchet mechanism for rotating said nut.
- 15 70. In a mining apparatus, a machine frame, a motor thereon, a pivoted cutter bar, a circulating cutter chain thereon, means for supporting said bar for bodily adjustment on said frame including a plurality of horizontal longitudinally pivoted turret elements, and means operable by said motor to selectively turn either or both of said turret elements or swing said bar, and to drive said chain or leave it idle.
- 20 71. In a mining apparatus, a truck frame, mechanism including cutting devices and actuating means therefor adjustably mounted on said truck frame, and means for effecting adjustment of said mechanism relative to said truck frame including an actuating member movable longitudinally of said frame, a pivoted member fixed save for pivotal movement connected at one end to said truck frame and operatively connected at its other end to said mechanism, and means connecting said actuating member and said last mentioned member to cause the end of said last mentioned member operatively connected to said mechanism to move to positions in different horizontal planes.
- 25 72. In a mining apparatus, a truck frame having supporting means, mechanism including cutting devices, a motor actuating the same, and a truck driving member adjustably mounted on said frame, operative connections between said truck driving member and said supporting means, and means for effecting adjustment of said mechanism relative to said truck frame without interrupting the operative connections between the truck driving member and truck wheels including an actuating member movable longitudinally of said frame, a pivoted member fixed save for pivotal movement connected at one end to said truck frame and operatively connected at its other end to said mechanism, and means connecting said actuating member and said last mentioned member to cause the end of said last mentioned member operatively connected to said mechanism to move to positions in different horizontal planes.
- 30 73. In a mining apparatus, a truck frame, cutting means thereon including a motor mounted on said frame, and means driven from the opposite ends of said motor shaft for respectively effecting propulsion of the frame through truck wheel drive at a cutting speed during cutting and at a substantially more rapid moving speed during running around a mine, both while the motor speed is substantially constant.
- 35 74. In a mining machine, a portable frame, cutting means thereon including a motor mounted on said frame, and means driven from the opposite ends of said motor shaft for respectively effecting feed of said frame as a whole during cutting and feed during running around the mine, the means for effecting feed during cutting comprising reverse mechanism permitting reversal of feed while the cutting means operates continuously in one direction. 80
- 40 75. In a mining machine, a portable frame provided with running gear, cutting means thereon including a motor mounted on said frame, and running gear driving means driven from the opposite ends of said motor shaft for respectively effecting feed of said frame as a whole during cutting and feed during running around the mine. 85
- 45 76. In a mining machine, a portable frame provided with running gear, cutting means thereon including a motor mounted on said frame, and running gear driving means driven from the opposite ends of said motor shaft for respectively effecting feed of said frame as a whole during cutting and feed during running around the mine, the means for effecting feed during cutting comprising reverse mechanism permitting reversal of feed while the cutting means operates continuously in one direction. 90
- 50 77. In a mining machine, a portable frame provided with running gear, cutting means thereon including a motor mounted on said frame, and running gear driving means driven from the opposite ends of said motor shaft for respectively effecting feed of said frame as a whole during cutting and feed during running around the mine, the means for effecting feed during cutting comprising reverse mechanism permitting reversal of feed while the cutting means operates continuously in one direction. 95
- 55 78. In a mining machine, a truck frame, means for effecting translation thereof including a truck wheel, a rotatable driving member for said truck wheel, a plurality of rotatable sprocket elements constantly connected for rotation with said rotatable driving member and adapted selectively to constitute driving members for the latter, driving means for said rotatable elements, and mechanism between said driving means and said elements operative to connect them in driven relation to said driving means or to permit free rotation thereof. 100
- 60 79. In a mining machine, a truck frame, means for effecting translation thereof including a truck wheel, a rotatable driving member for said truck wheel, a plurality of rotatable elements constantly connected for rotation with said rotatable driving member and adapted selectively to constitute driving members for the latter, driving means for said rotatable elements rotatable at different predetermined rates, and mechanism between said driving means and said elements operative to connect them in driven relation to said driving means or to permit free rotation thereof. 105
- 65 80. In a mining machine, a truck frame, a truck wheel, a rotatable driving member for said truck wheel, a plurality of rotatable elements constantly connected for rotation with said rotatable driving member and adapted selectively to constitute driving members for the latter, driving means for said rotatable elements and mechanism between said driving means and said elements operative to connect them in driven relation to said driving means or to permit free rotation thereof. 110
- 70 81. In a mining machine, a truck frame, means for effecting translation thereof including a truck wheel, a rotatable driving member for said truck wheel, a plurality of rotatable elements constantly connected for rotation with said rotatable driving member and adapted selectively to constitute driving members for the latter, driving means for said rotatable elements rotatable at different predetermined rates, and mechanism between said driving means and said elements operative to connect them in driven relation to said driving means or to permit free rotation thereof. 115
- 75 82. In a mining machine, a wheeled truck frame adapted to travel along a mine trackway, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 120
- 80 83. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 125
- 85 84. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 130
- 90 85. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 135
- 95 86. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 140
- 100 87. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 145
- 105 88. In a mining machine, a wheeled truck frame, a machine body pivotally mounted on said frame for tilting movement relative thereto on a transverse axis, a cutter carrying head mounted on said body for rotation about a longitudinal axis, a cutter bar pivotally mounted on said head for swinging movement about an axis perpendicular to said head axis, a motor carried by said body, mechanism driven by said motor for rotating said head to move said bar into parallel planes and for swinging said bar about its pivot, and mechanism driven by said motor for propelling the machine along the mine trackway. 150

- itudinal axis, a cutter bar pivotally mounted on said head for swinging movement about an axis perpendicular to said head axis, a motor carried by said body, and mechanism driven by said 5 motor for rotating said head and for swinging said bar about its pivot at a predetermined fast bar positioning speed in one direction and at a predetermined slow cutting speed in the opposite direction.
- 10 72. In a mining machine, a wheeled truck frame, a machine body pivotally mounted on said frame for tilting movement relative thereto on a transverse axis, a frame mounted on said body for rotation about a longitudinal axis, a 15 cutter carrying head mounted on said last mentioned frame for rotation about a longitudinal axis parallel to said frame axis, a cutter bar pivotally mounted on said head for swinging movement about an axis perpendicular to said 20 head axis, a motor carried by said body, and mechanism driven by said motor for rotating said frame relative to said body, for rotating said head relative to said frame and for swinging said bar about its pivot.
- 25 73. In a mining machine, a wheeled truck frame adapted to travel along a mine trackway, a machine body pivotally mounted on said frame for tilting movement relative thereto on a transverse axis, a cutter carrying head mounted on 30 said body for rotation about a longitudinal axis, a cutter bar mounted on said head for swinging movement relative thereto and disposed in a plane offset from said head axis, a motor carried by said body, mechanism driven by said 35 motor for rotating said head to effect orbital movement of said bar about said head axis and for swinging said bar about its pivot, and mechanism driven by said motor for driving the truck wheels to propel the machine along the mine 40 trackway.
- 45 74. In a mining machine, a wheeled truck frame, a machine body pivotally mounted thereon for tilting movement relative thereto on a transverse axis, a frame mounted on said body for rotation about a longitudinal axis, a cutter carrying head mounted on said rotatable frame for rotation about a longitudinal axis parallel to said frame axis, a cutter bar pivotally mounted on said head for swinging movement relative 50 thereto and disposed in a plane offset from said head axis, a motor carried by said body, and mechanism driven by said motor for rotating said rotatable frame, for rotating said head to effect orbital movement of said cutter bar about said 55 head axis and for swinging said bar about its pivot.
- 60 75. In a mining machine, a wheeled truck frame, a machine body mounted thereon, a frame mounted on said body for rotation about a longitudinal axis, a cutter carrying head rotatably mounted on said rotatable frame for rotation about a longitudinal axis parallel to said frame axis, a cutter bar pivotally mounted on said head for swinging movement relative thereto, to, a motor carried by said body, and mechanism driven by said motor for simultaneously rotating said rotary frame and said head about their respective axes.
- 65 76. In a mining machine, a machine body, a motor carried thereby, cutting mechanism including a cutter bar mounted on said body for swinging movement relative thereto, and mechanism driven by said motor for effecting swinging movement of said bar selectively at predetermined fast and slow speeds comprising alter-
- natively operable fast and slow speed worm gear trains, said bar being swung at one speed through one gear train and at another speed through the other gear train.
77. In a mining machine, a machine body, a motor carried thereby, cutting mechanism including a cutter bar mounted on said body for swinging movement relative thereto, and mechanism driven by said motor for effecting swinging movement of said bar at a plurality of predetermined speeds comprising alternatively effective fast and slow speed worm gearings and friction clutch means controlling the connection of said gearings to said motor.
78. In a mining machine, a machine body, a motor carried thereby, cutting mechanism including a cutter bar pivotally mounted on said body for swinging movement relative thereto, and mechanism driven by said motor for effecting swinging movement of said bar at a plurality of predetermined speeds comprising coaxial fast and slow speed worms, worm gears meshing therewith disposed on parallel axes, driving connections between said worm gears and said bar, and friction clutch means controlling the connection of said worms to said motor.
79. In a mining machine, a machine body, a motor carried thereby, cutting mechanism comprising a cutter bar pivotally mounted on said body for swinging movement relative thereto, and mechanism driven by said motor for effecting swinging movement of said bar at predetermined fast and slow speeds in opposite directions comprising alternatively operable fast and slow speed worm gear trains, said bar being swung at one speed through one gear train and at another speed through the other gear train.
- 80 81. In a mining machine, a machine body, a motor carried thereby, cutting mechanism comprising a cutter bar pivotally mounted on said body for swinging movement relative thereto, and mechanism driven by said motor for effecting swinging movement of said bar at a plurality of predetermined speeds in opposite directions comprising alternatively effective fast and slow speed worm gearings and friction clutch means controlling the connection of said gearings to said motor.
- 85 82. In a mining machine, a wheeled truck frame, a machine body pivotally mounted on said frame for tilting movement relative thereto on a transverse axis, a motor carried by said body, a cutter carrying head mounted on said body for rotation about a longitudinal axis, mechanism driven by said motor for effecting rotation of said head, and mechanism driven by said motor for driving the wheels of said truck frame irrespective of the position of said body relative to the truck wheels.
- 90 83. In a mining machine, a wheeled truck frame, a machine body pivotally mounted thereon for tilting movement relative thereto on a transverse axis, a motor carried by said body having its power shaft extending longitudinally of said body, a cutter carrying head mounted on said body for rotation about a longitudinal axis, mechanism driven from the forward end of said motor for effecting rotation of said head, and mechanism driven from the rear end of said motor for driving the wheels of said truck 95 irrespective of the position of said body relative to the truck wheels.
- 95 84. In a mining machine, a wheeled truck frame, a machine body pivotally mounted thereon for tilting movement relative thereto on a

- transverse axis, a motor carried by said body having its power shaft extending longitudinally of said body, a cutter carrying head mounted on said body for rotation about a longitudinal axis, a cutter bar pivotally mounted on said head and carrying an orbitally movable cutter chain, mechanism driven from the forward end of said motor for effecting rotation of said head, for swinging said bar about its pivot and for actuating said cutter chain, and mechanism driven from the rear end of said motor for driving the wheels of said truck irrespective of the position of said body relative to the truck wheels.

15 84. In a mining machine, a wheeled truck frame, a machine body pivotally mounted thereon for tilting movement relative thereto on a transverse axis, a motor carried by said body having its axis extending longitudinally of said body, a frame mounted on said body for rotation about a longitudinal axis, a cutter carrying head mounted on said frame for rotation about a parallel axis, mechanism driven from the forward end of said motor for effecting rotation of said head and frame about their respective axes, and mechanism driven from the rear end of said motor for driving the wheels of said truck irrespective of the position of said body relative to the truck wheels.

20 85. In a mining machine, a wheeled truck frame, a machine body pivotally mounted thereon for tilting movement relative thereto on a transverse axis, a motor carried by said body having its power shaft extending longitudinally of said body, a frame mounted on said body for rotation about a longitudinal axis, a cutter carrying head mounted on said frame for rotation about a parallel axis, mechanism driven from the rear end of said motor for driving the wheels of said truck at a transport speed, and mechanism driven from the front end of said motor for driving the wheels of said truck at a different speed irrespective of the position of said body relative to the truck wheels.

25 86. In a mining machine, a wheeled truck frame, a machine body pivotally mounted thereon for tilting movement relative thereto on a transverse axis, a motor carried by said body having its power shaft extending longitudinally of said body, a frame mounted on said body for rotation about a longitudinal axis, a cutter carrying head rotatably mounted on said frame for rotation about a parallel axis, a cutter chain carrying cutter bar pivotally mounted on said head, mechanism driven from the forward end of said motor for rotating said head and frame about their respective axes, for swinging said bar about its pivot, and mechanism driven from the rear end of said motor for driving the wheels of said truck irrespective of the position of said body relative to the truck wheels.

30 87. In a mining machine, a wheeled truck frame, a machine body pivotally mounted thereon to rock on a transverse axis, a motor carried by said body, a cutter carrying head mounted on said body for rotation about a longitudinal axis, mechanism driven by said motor for effecting rotation of said head, mechanism driven by said motor for driving the wheels of said truck frame at a transport speed, and mechanism driven from the front end of said motor for driving the wheels of said truck at a different speed irrespective of the position of said body relative to the truck wheels.

35 88. In a mining machine, a wheeled truck frame, a machine body pivotally mounted thereon to rock on a transverse axis, a motor carried by said body having its power shaft extending longitudinally of said body, a cutter carrying head mounted on said body for rotation about a longitudinal axis, mechanism driven from the forward end of said motor for effecting rotation of said head, mechanism driven from the rear end of said motor for driving the wheels of said truck at a transport speed, and mechanism driven from the front end of said motor for driving the wheels of said truck at a different speed irrespective of the position of said body relative to the truck wheels.

40 89. In a mining machine, a wheeled truck frame, a machine body pivotally mounted thereon to rock or a transverse axis, a motor carried by said body having its axis extending longitudinally of said body, a frame mounted on said body for rotation about a longitudinal axis, a cutter carrying head mounted on said frame for rotation about a parallel axis, mechanism driven from the forward end of said motor for effecting rotation of said head and frame about their respective axes, mechanism driven from the rear end of said motor for driving the wheels of said truck at a transport speed, and mechanism driven from the front end of said motor for driving the wheels of said truck at a different speed irrespective of the position of said body relative to the truck wheels.

45 90. In a mining machine, a wheeled truck frame, a machine body pivotally mounted thereon to rock on a transverse axis, a motor carried by said body having its power shaft extending longitudinally of said body, a frame mounted on said body for rotation about a longitudinal axis, a cutter carrying head rotatably mounted on said frame for rotation about a parallel axis, a cutter chain carrying cutter bar pivotally mounted on said head, mechanism driven from the forward end of said motor for rotating said head and frame about their respective axes and for swinging said bar about its pivot, mechanism driven from the rear end of said motor for driving the wheels of said truck at a transport speed, and mechanism driven from the front end of said motor for driving the wheels of said truck at a different speed irrespective of the position of said body relative to the truck wheels.

50 91. In a mining machine, a wheeled truck frame, a machine body pivotally mounted thereon for tilting movement relative thereto on a transverse axis, a frame mounted on said body for rotation about a longitudinal axis, a cutter carrying head rotatably mounted on said frame for rotation about a parallel axis, a cutter bar mounted on said head for swinging movement relative thereto and disposed in a plane offset from said head axis, and mechanism driven by said motor for effecting orbital movement of said bar about either the axis of said head or the axis of said rotatable frame.

55 92. In a mining machine, a wheeled truck frame adapted to travel along a mine trackway, a machine body pivotally mounted on said frame for tilting movement relative thereto on a transverse axis disposed intermediate the truck wheel axes, a cutter carrying head mounted on said body for rotation about a longitudinal axis, a

- 80 cutter bar pivotally mounted on said head for swinging movement relative thereto, a motor carried by said body, mechanism driven by said motor for rotating said head and for swinging said bar about its pivot, and mechanism driven by said motor for driving the truck wheels to propel the machine along the mine trackway.
- 85 93. In a mining machine, a machine body, a motor carried by said body, a cutter carrying head rotatably mounted on said body for rotation about a longitudinal axis, mechanism driven by said motor for effecting rotation of said head, and releasable means cooperating with an element of said head rotating mechanism for locking said head in its different adjusted positions.
- 90 94. In a mining machine, a machine body, a motor carried thereby, a cutter carrying head rotatably mounted on said body for rotation about a longitudinal axis, mechanism driven by said motor for effecting rotation of said head including a gear fixed to said head, and releasable means cooperating with said gear for locking said head in its different adjusted positions.
- 95 95. In a mining machine, a machine body, a motor carried thereby, a frame rotatably mounted on said body for rotation about a longitudinal axis, a cutter carrying head rotatably mounted on said frame for rotation about a longitudinal axis parallel to said frame axis, mechanism driven by said motor for effecting rotation of said frame and said head about their respective axes, and independently operable releasable means cooperating with said head and frame rotating mechanism for locking said head and frame in their different adjusted positions.
- 100 96. In a mining machine, a machine body, a motor carried thereby, a frame rotatably mounted on said body for rotation about a longitudinal axis, a cutter carrying head rotatably mounted on said frame for rotation about a longitudinal axis parallel to said frame axis, mechanism driven by said motor for independently effecting rotation of said head and frame about their respective axes including a gear fixed to said head and a gear fixed to said frame, and independently operable releasable means cooperating with said gears for locking said head and frame in their different adjusted positions.
- 105 97. In a mining machine, a machine body, a motor carried thereby, cutting mechanism including a cutter bar mounted on said body for swinging movement relative thereto, and mechanism driven by said motor for effecting swinging movement of said bar at a plurality of predetermined speeds, comprising fast and slow speed worms, worm gears meshing respectively therewith, and driving connections between said worm gears and said bar, said mechanism including manually operable clutches for effecting bar swing by said worms alternatively.
- 110 98. In a mining machine, a machine body, a motor carried thereby, cutting mechanism including a cutter bar mounted on said body for swinging movement relative thereto, mechanism driven by said motor for effecting swinging movement of said bar at a plurality of predetermined speeds comprising alternatively effective fast and slow speed worms, worm gears meshing respectively therewith, pinions rotating with said worm gears, a gear meshing with said pinions, and driving connections between said gear and said bar.
- 115 99. In a mining machine, a machine body, a motor carried thereby, cutting mechanism including a cutter bar mounted on said body for swinging movement relative thereto, mechanism driven by said motor for effecting swinging movement of said bar at a plurality of predetermined speeds comprising alternatively effective fast and slow speed worms, worm gears meshing respectively therewith, pinions rotating with said worm gears, a gear meshing with said pinions, and driving connections between said gear and said bar.
- 120 100. In a mining machine, a machine body, a motor carried thereby, cutting mechanism including a cutter bar mounted on said body for swinging movement relative thereto, mechanism driven by said motor for effecting swinging movement of said bar at a plurality of predetermined speeds comprising alternatively effective fast and slow speed worms, worm gears meshing respectively therewith, pinions rotating with said worm gears, a gear meshing with said pinions, a pinion rotatable with said last mentioned gear, and a circular rack fixed to said bar and with which said last mentioned pinion meshes.
- 125 101. In a mining machine, a machine body, a motor carried thereby, cutting mechanism including a cutter bar mounted on said body for swinging movement relative thereto, and mechanism driven by said motor for effecting swinging movement of said bar at a plurality of predetermined speeds comprising alternatively effective fast and slow speed worms, worm gears meshing respectively therewith, pinions rotating with said worm gears, a gear meshing with said pinions, a pinion rotatable with said last mentioned gear, a circular rack fixed to said bar and with which said last mentioned pinion meshes, and selectively operable friction clutches for effecting bar swing alternatively by said worms in opposite directions.
- 130 102. In a mining machine, a wheeled support adapted to run along a mine trackway and mounted for tilting movement about a transverse axis, cutting mechanism on said support including a cutter carrying head mounted on said support for rotation relative thereto about an axis extending longitudinally of the trackway, a cutter bar pivotally mounted on said head for swinging movement about an axis perpendicular to said head axis, a motor carried by said pivoted support, mechanism driven by said motor for rotating said head relative to said support and said motor to move said cutter bar into different planes, mechanism driven by said motor for swinging said bar about its pivot, said head rotating mechanism being operative wholly independently of said bar swinging mechanism, and mechanism driven by said motor for driving the support wheels to propel the machine along the mine trackway.
- 135 103. In a mining machine, a wheeled support adapted to run along a mine trackway, adjustable cutting mechanism on said support including a frame mounted on said support for rotation about a longitudinal axis, a cutter carrying head mounted on said frame for rotation about a horizontal axis parallel to said frame axis, a cutter bar pivotally mounted on said head for swinging movement relative thereto, a motor carried by said support, mechanism driven by said motor for effecting swinging movement of said cutter bar, and mechanism driven by said motor and operative independently of said bar

- swinging mechanism for rotating said frame relative to said support and for rotating said head relative to said frame.
104. In a mining machine, a wheeled support adapted to run along a mine trackway, adjustable cutting mechanism on said support including a frame mounted on said support for rotation about a longitudinal axis, a cutter carrying head mounted on said frame for rotation about a longitudinal axis parallel to said frame axis, a cutter bar pivotally mounted on said head for swinging movement relative thereto, motor operated devices for effecting simultaneous adjustment of said frame and head about their respective axes, and motor operated devices for driving said cutting mechanism and for swinging said cutter bar about its pivot. 80
105. In a mining machine, a wheeled support adapted to run along a mine trackway, adjustable cutting mechanism thereon including a frame mounted on said support for rotation about a longitudinal axis, a cutter carrying head mounted on said frame for rotation about a longitudinal axis parallel with said frame axis, a cutter bar pivotally mounted on said head for swinging movement relative thereto, a motor carried by said support, mechanism driven by said motor and carried by said support for rotating said frame about its axis, mechanism driven by said motor and carried by said head for rotating said head about its axis relative to said frame, and motor operated devices for driving said cutting mechanism and for swinging said cutter bar about its pivot. 95
106. In a mining machine, a wheeled truck frame adapted to run along a mine trackway, a frame pivotally mounted on said truck frame for tilting movement relative thereto about a transverse axis intermediate the wheel axes, a motor carried by said pivoted frame, cutting mechanism on said frame including a cutter carrying head mounted on said frame for rotation about a longitudinal axis and a cutter bar pivotally mounted on said head for swinging movement relative thereto, mechanism driven by said motor for rotating said head relative to said frame to move said bar into different planes and for swinging said cutter bar about its pivot, and mechanism driven by said motor for driving the truck wheels to propel the machine along the mine trackway. 100
107. In a mining machine, a wheeled support adapted to run along a mine trackway, adjustable cutting mechanism thereon including a frame mounted on said support for rotation about a longitudinal axis, a cutter carrying head mounted on said frame for rotation about a longitudinal axis parallel with said frame axis, a cutter bar pivotally mounted on said head for swinging movement relative thereto, a motor carried by said support, mechanism driven by said motor for driving said cutting mechanism including a drive shaft coaxial with the pivot for said head and gearing connecting said shaft with said cutting mechanism, mechanism driven by said shaft for rotating said head relative to said frame, and motor operated mechanism for rotating said frame relative to said support and for swinging said cutter bar about its pivot. 110
108. In a mining machine, a wheeled support adapted to run along a mine trackway, adjustable cutting mechanism thereon including a frame mounted on said support for rotation about a longitudinal axis, a cutter carrying head mounted on said frame for rotation about a lon-
- gitudinal axis parallel with said frame axis, a cutter bar pivotally mounted on said head for swinging movement relative thereto, motor operated devices for independently adjusting said frame and head about their respective axes, and motor operated devices operable independently of said frame and head adjusting devices for swinging said cutter bar about its pivot. 120
109. In a mining machine, a frame, a cutter bar pivotally mounted thereon, and motor operated devices for swinging said cutter bar relative to said frame including a frictionally controlled low speed gear train for effecting bar swing at a cutting speed in one direction and a separate frictionally controlled high speed gear train for effecting bar swing at a relatively high bar positioning speed. 125
110. In a mining machine, a frame, a cutter bar pivotally mounted thereon, and motor operated devices for swinging said cutter bar relative to said frame including a frictionally controlled low speed gear train for effecting bar swing at a cutting speed in one direction and a separate frictionally controlled high speed gear train for effecting bar swing in the opposite direction at a relatively high bar positioning speed. 130
111. In a mining machine, a frame, a cutter bar pivotally mounted thereon, and motor operated devices for swinging said cutter bar relative to said frame including a frictionally controlled low speed worm gear train for effecting bar swing at a cutting speed in one direction, and a separate frictionally controlled high speed worm gear train for effecting bar swing in the opposite direction at a relatively high bar positioning speed, said worm gear trains being self-locking for automatically maintaining the cutter bar in its adjusted position. 135
112. In a mining apparatus, a wheeled support adapted to run along a trackway, a motor thereon having its axis extending longitudinally of said support, cutting mechanism on said support including a cutter carrying head mounted on said support for rotation about a longitudinal axis and a cutter bar pivotally mounted on said head for swinging movement relative thereto, and mechanism driven from the front end of said motor for driving said cutting mechanism, for rotating said head, for swinging said cutter bar and for driving the support wheels to propel the apparatus along the trackway. 140
113. In a mining apparatus, a wheeled support adapted to run along a trackway, a motor thereon having its axis extending longitudinally of said support, cutting mechanism on said support including a cutter carrying head mounted on said support for rotation about a longitudinal axis and a cutter bar pivotally mounted on said head for swinging movement relative thereto, mechanism driven from the front end of said motor for driving said cutting mechanism, for rotating said head, for swinging said cutter bar and for driving the support wheels to propel the apparatus along the trackway at a cutting speed, and mechanism driven from the rear end of said motor for driving the support wheels at a relatively fast transport speed. 145
114. In a mining apparatus, a wheeled support adapted to run along a mine trackway, a motor thereon having its axis extending longitudinally of said support, cutting mechanism on said support including a frame mounted on said support for rotation about a longitudinal axis, a cutter carrying head mounted on said

- frame for rotation about a longitudinal axis parallel to said frame axis and a cutter bar pivotally mounted on said head for swinging movement relative thereto, and mechanism driven from the front end of said motor for driving said cutting mechanism, for rotating said head and frame about their respective axes, for swinging said cutter bar and for driving the support wheels to propel the apparatus along the trackway.
115. In a mining apparatus, a wheeled support adapted to run along a mine trackway, a motor thereon having its axis extending longitudinally of said support, cutting mechanism on said support including a frame mounted on said support for rotation about a longitudinal axis, a cutter carrying head mounted on said frame for rotation about a longitudinal axis parallel to said frame axis and a cutter bar pivotally mounted on said head for swinging movement relative thereto, mechanism driven from the front end of said motor for driving said cutting mechanism, for rotating said head and frame about their respective axes, for swinging said cutter bar and for driving the support wheels to propel the apparatus along the trackway at a cutting speed, and mechanism driven from the rear end of said motor for driving the support wheels at a relatively fast transport speed.
116. In a mining apparatus, a wheeled support adapted to run along a mine trackway, cutting mechanism on said support including a cutter carrying head rotatable relative to said support about a longitudinal axis and a cutter bar pivotally mounted on said head for swinging movement relative thereto, motor operated devices for driving said cutting mechanism and for effecting bar swing, and motor operated devices for rotating said head in opposite directions and for driving the support wheels to propel the apparatus in opposite directions along the mine trackway and including a frictionally controlled reversing mechanism controlling both said head rotating and wheel driving devices.
117. In a mining apparatus, a wheeled support adapted to run along a mine trackway, cutting mechanism on said support including a cutter carrying head rotatable relative to said support about a longitudinal axis and a cutter bar pivotally mounted on said head for swinging movement relative thereto, motor operated devices for driving said cutting mechanism and for effecting bar swing, motor operated devices for rotating said head in opposite directions and for driving the support wheels to propel the apparatus in opposite directions along the mine trackway and including a frictionally controlled reversing mechanism controlling both said head rotating and wheel driving devices, and separate operator-controlled controlling clutches for each of said devices whereby said head may be rotated and said support wheels driven independently.
118. In a mining machine, a frame, cutting mechanism including a cutter bar pivotally mounted on said frame for swinging movement relative thereto, and motor operated mechanism for effecting bar swing including a gear secured to said cutter bar, a pinion meshing therewith, and separate frictionally controlled fast and slow speed gear trains for effecting selectively rotation of said pinion at a relatively fast speed in one direction and at a relatively slow speed in the opposite direction and including friction
- controlling clutches one individual to each gear train.
119. In a mining machine, a frame, cutting mechanism including a cutter bar pivotally mounted on said frame for swinging movement relative thereto, and motor operated devices for effecting bar swing in opposite directions including a frictionally controlled reversing device, said device including separate gear trains each having a friction controlling clutch yieldable upon overload of said bar swinging devices.
120. In a mining apparatus, a wheeled truck adapted to run along the mine trackway, cutting mechanism on said truck including a cutter carrying head rotatable about a longitudinal axis and a cutter chain carrying cutter bar pivotally mounted on said head for swinging movement relative thereto, a motor on said truck, driving connections between said motor and said cutter chain, and mechanism driven directly from said connections between said motor and said cutter chain for effecting rotation of said cutter head and for driving the truck wheels to propel the apparatus along the mine trackway.
121. In a mining apparatus, a wheeled truck adapted to run along a mine trackway, cutting mechanism on said truck including a cutter carrying head rotatable about a longitudinal axis and a cutter chain carrying cutter bar pivotally mounted on said head for swinging movement relative thereto, a motor on said truck, mechanism driven by said motor for effecting bar swing and for driving said cutter chain, and mechanism driven directly by an element of said mechanism for effecting head rotation and for driving the truck wheels to propel the apparatus along the mine trackway.
122. In a machine of the class described, a support, a substantially horizontally extending cutter bar, mounting means for the cutter bar in connection with said support including gearing mechanisms whereby the bar is movable relative to the support about two axes at right angles to each other, a sprocket shaft for the cutter bar journaled in said mounting means in coincidence with one of said axes, a gear freely revoluble on said shaft, means for driving said gear, and selectively operable drive connections between said gear, said sprocket shaft and said gearing mechanisms.
123. In a mining machine, a wheeled support adapted to travel along a mine trackway, a cutter head mounted on the forward end of said support for rotation relative thereto about a longitudinal axis, a cutter bar pivotally mounted on said cutter head for swinging movement relative thereto about an axis perpendicular to the axial line of the cutter head, said bar carrying a cutter chain, motor operated devices for driving said cutter chain including a motor on said support relative to which said cutter head is rotatable and having a power shaft, a shaft driven by said motor power shaft and extending longitudinally of the support and journaled thereon and gearing connecting said shaft in driving relation with the cutter chain, devices driven by said longitudinal shaft for rotating the cutter head about its axis, and devices driven by said shaft for driving the support wheels and including a parallel shaft, gearing connecting said shafts and gearing connecting said parallel shaft in driving relation with the support wheels.
124. In a mining machine, a wheeled support adapted to travel along a mine trackway, a cutter head mounted on the forward end of said

- support for rotation relative thereto about a longitudinal axis, a cutter bar pivotally mounted on said cutter head for swinging movement relative thereto about an axis perpendicular to the axial line of the cutter head, said bar carrying a cutter chain, motor operated devices for driving said cutter chain including a motor on said support relative to which said cutter head is rotatable and having a power shaft, a shaft 5 driven by said motor power shaft and extending longitudinally of the support and journaled thereon and gearing connecting said shaft in driving relation with the cutter chain, devices driven by said longitudinal shaft for rotating said cutter head about its axis, and devices 10 driven by said shaft for driving the support wheels and including a parallel shaft, gearing connecting said shafts including clutch controlled reversing gears for driving said parallel shaft in either of opposite directions while said first shaft rotates continuously in the same direction, and gearing connecting said parallel shaft in driving relation with the support 15 wheels.
125. In a mining machine, a wheeled support adapted to travel along a mine trackway, a cutter head mounted on the forward end of said support for rotation relative thereto about a longitudinal axis, a cutter bar pivotally mounted on said cutter head for swinging movement relative thereto about an axis perpendicular to the axial line of the cutter head, said bar carrying a cutter chain, motor operated devices for driving said cutter chain including a motor 20 on said support relative to which said cutter head is rotatable and having a power shaft, a shaft driven by said motor power shaft and extending longitudinally of the support and journaled thereon and gearing connecting said shaft in driving relation with the cutter chain, and devices 25 driven by said shaft for driving the support wheels and including a parallel shaft, and gearings connecting said shafts in driving relation and the parallel shaft in driving relation with the support wheels and including clutch controlled reversing gears.
126. In a mining machine, a wheeled support adapted to travel along a mine trackway, a cutter head mounted on the front end of the support for rotation relative thereto about a longitudinal axis, a cutter bar pivotally mounted on said cutter head to swing relative thereto about 30 an axis perpendicular to the axial line of the cutter head, said bar carrying a cutter chain, motor operated devices for driving said cutter chain including a shaft extending longitudinally of said support and journaled thereon and gearing connecting said shaft in driving relation with the cutter chain, devices driven by said longitudinal shaft for rotating said cutter head about its axis including a transverse shaft and gearing connecting said transverse shaft in operating 35 relation with the cutter head, and devices driven by said longitudinal shaft for driving the support wheels and including a parallel longitudinally extending shaft and gearing connecting said parallel shaft in driving relation with the support wheels.
127. In a mining machine, a wheeled support adapted to travel along a mine trackway, a cutter head mounted on the front end of the support for rotation relative thereto about a longitudinal axis, a cutter bar pivotally mounted on 40 said cutter head to swing relative thereto about an axis perpendicular to the axial line of the cutter head, said bar carrying a cutter chain, motor operated devices for driving said cutter chain including a shaft extending longitudinally of said support and journaled thereon and gearing connecting said shaft in driving relation with the cutter chain, devices driven by said longitudinal shaft for rotating said cutter head about its axis including a transverse shaft and gearing connecting said transverse shaft in operating 45 relation with the cutter head, and devices driven by said longitudinal shaft for driving the support wheels and including a parallel longitudinally extending shaft and gearing connecting said parallel shaft in driving relation with the support wheels.
128. In a mining machine, a wheeled support adapted to travel along a mine trackway, a cutter head mounted on the front end of the support for rotation relative thereto about a longitudinal axis, a cutter bar pivotally mounted on said cutter head to swing relative thereto about an axis perpendicular to the axial line of the cutter head, said bar carrying a cutter chain, motor operated devices for driving said cutter chain including a shaft extending longitudinally of said support and journaled thereon and gearing connecting said shaft in driving relation with the cutter chain, and devices 50 driven by said shaft for rotating said cutter head and driving the support wheels in either of opposite directions while said shaft rotates continuously in the same direction including a transverse shaft, clutch-controlled reversing gears coaxial with said latter shaft and a shaft parallel with said longitudinal shaft.
129. In a mining machine, a wheeled support adapted to travel along a mine trackway, a cutter head mounted on the front end of said support for rotation about a longitudinal axis, a cutter bar pivotally mounted on said head to swing relative thereto, and motor operated devices for rotating said head and driving the support wheels including a shaft extending longitudinally of said support and journaled thereon, a parallel shaft, gearing connecting said shafts, gearing driven from the forward end of said parallel shaft for rotating said head, and gearing driven from the rear end of said parallel 55 shaft for driving the support wheels.
130. In a mining machine, a wheeled support adapted to travel along a mine trackway, a cutter head mounted on the front end of said support for rotation about a longitudinal axis, a cutter bar pivotally mounted on said head to swing relative thereto, and motor operated devices for rotating said head and driving the support wheels including a shaft extending longitudinally of said support and journaled thereon, a parallel shaft, gearing connecting said shafts, gearing driven from the forward end of said parallel shaft for rotating said head, and gearing driven from the rear end of said parallel shaft for driving the support wheels, said head rotating devices including a transverse shaft driven by said first shaft and clutch-controlled reversing gears coaxial with said transverse shaft.
131. In a mining machine, a wheeled support adapted to travel along a mine trackway, a 60

- 5 cutter head mounted on the front end of said support for rotation about a longitudinal axis, a cutter bar pivotally mounted on said head to swing relative thereto, and motor operated devices for rotating said head and driving the support wheels both in either of opposite directions including a shaft extending longitudinally of said support and journaled thereon, a parallel shaft, gearing connecting said shafts, gearing 80
 10 driven from the forward end of said parallel shaft for driving the head rotating devices, and gearing driven from the rear end of said parallel shaft for driving the support wheels.
132. In a mining machine, a wheeled support adapted to travel along a mine trackway, a cutter head mounted on the front end of said support for rotation about a longitudinal axis, a cutter bar pivotally mounted on said head to swing relative thereto, and motor operated devices for 85
 15 rotating said head and driving the support wheels both in either of opposite directions including a shaft extending longitudinally of said support and journaled thereon, a parallel shaft, gearing connecting said shafts, gearing 90
 20 driven from the forward end of said parallel shaft for driving the head rotating devices, and gearing driven from the rear end of said parallel shaft for driving the support wheels, said head rotating devices including a transverse 95
 25 shaft and clutch-controlled reversing gears coaxial with said transverse shaft.
133. In a mining machine, a wheeled truck adapted to travel along a mine trackway, a support pivotally mounted on said truck to rock relative thereto about a transverse axis offset from and parallel with the truck wheel axes, a cutter head mounted on the forward end of said support and tiltable therewith, a cutter bar pivotally mounted on said cutter head to swing relative thereto, motor operated devices for swinging said cutter bar about its pivot, motor operated devices for adjusting said cutter bar into parallel planes relative to said cutter head, and means for feeding said cutter bar longitudinally in a path parallel to the plane of the trackway irrespective of the adjusted position of the cutter bar and the tilted position of said cutter head. 100

139. In a mining machine, a wheeled truck adapted to travel along a mine trackway, a support mounted on said truck to rock relative thereto about a transverse axis intermediate the truck wheel axes, a cutter head mounted on the forward end of said support for rotation relative thereto about a longitudinal axis, a cutter bar pivotally mounted on said cutter head to swing relative thereto, motor operated devices for rotating said head about its axis and 150

- for swinging said cutter bar about its pivot, and motor operated devices for driving the truck wheels to propel the complete mining machine bodily along the mine trackway to effect sumping and withdrawal movements of said cutter bar.
140. In a mining machine, a wheeled truck adapted to travel along a mine trackway, a support mounted on said truck to rock relative thereto about a transverse axis intermediate the truck wheel axes, a cutter head mounted on the forward end of said support for rotation relative thereto about a longitudinal axis, a cutter bar pivotally mounted on said cutter head to swing relative thereto and adjustable with said cutter head into any position about the head axis, motor operated devices for rotating said head about its axis and for swinging said cutter bar about its pivot, motor operated devices for adjusting said cutter bar into parallel planes relative to said cutter head in any of aforesaid positions, and means for feeding said cutter bar longitudinally in a path parallel to the plane of the trackway irrespective of the adjusted position of the cutter bar and the tilted position of the cutter head.
141. In a mining machine, a wheeled truck adapted to travel along a mine trackway, a support mounted on said truck to rock relative thereto about a transverse axis intermediate the truck wheel axes, a cutter head mounted on the forward end of said support for rotation relative thereto about a longitudinal axis, a cutter bar pivotally mounted on said cutter head to swing relative thereto, motor operated devices for rotating said head about its axis and for swinging said cutter bar about its pivot, motor operated devices for adjusting said cutter bar into parallel planes relative to said cutter head, and means for driving the truck wheels to propel the complete mining machine bodily along the mine trackway to effect sumping and withdrawal movements of said cutter bar.
142. In a mining machine, a machine body, a cutter carrying head rotatably mounted thereon about a horizontal axis, and means for locking said head to said body including a rotatable member carried by said body and means for rotating said member.
143. In a mining machine, a machine body having a notched flange, a cutter carrying head rotatably mounted on said body about a horizontal axis, and means for locking said head to said body including a rotatable member engaging the notches in said flange and means for rotating said member.
144. In a mining machine, a machine body having a notched flange, a cutter carrying head rotatably mounted on said body about a horizontal axis, and means for locking said head to said body comprising a rotatable member having a groove therein receiving said flange and engageable with the notches in said flange and means for rotating said member.
145. In a mining apparatus, a supporting frame, a cutter head mounted on said frame for rotation relative thereto, a kerf cutter pivotally mounted on said cutter head, and mechanism for rotating said head and swinging said kerf cutter comprising a shaft journaled on said head, worms driven by said shaft, clutches for effecting rotation of said shaft in either of opposite directions, gearing driven by one of said worms for effecting head rotation, and gearing driven by said other worm for effecting swinging of said kerf cutter.
146. In a mining apparatus, a portable base, supporting means in the form of an arm structure pivotally mounted on said base to swing in a vertical direction relative thereto about a horizontal axis extending transversely of said base, means between said base and supporting means for swinging the latter as aforesaid, a cutter head mounted on the forward extremity of said supporting means for rotation relative thereto about an axis extending longitudinally of said supporting means, a kerf cutter pivotally mounted on said cutter head to swing relative thereto about an axis at right angles to the head axis, and means for propelling said base bodily toward and from the coal face to effect rectilinear sumping and withdrawal movements of said kerf cutter.
147. In a mining apparatus, a portable base, supporting means in the form of an arm structure pivotally mounted on said base to swing in a vertical direction relative thereto about a horizontal axis extending transversely of said base, means between the base and supporting means for swinging the latter as aforesaid, a support mounted on the forward extremity of said supporting means for rotation relative thereto about an axis extending longitudinally of said supporting means, a cutter support rotatably mounted on said first support and a kerf cutter pivotally mounted on said cutter support to swing relative thereto about an axis at right angles to the axis of the first support, and means for propelling said base bodily toward and from the coal face to effect rectilinear sumping and withdrawal movements of said kerf cutter.
148. In a mining apparatus, a wheeled truck adapted to run along a mine trackway, supporting means in the form of an arm structure pivotally mounted on said truck to swing in a vertical direction relative thereto about a horizontal axis extending transversely of said truck and located at the forward end of the truck adjacent to but spaced from the front truck wheel axes, a support rotatably mounted on the forward extremity of said supporting means for rotation relative thereto about an axis extending longitudinally of said supporting means, a cutter support rotatably mounted on said first support, a kerf cutter pivotally mounted on said cutter support for swinging movement relative thereto about an axis at right angles to the axis of said first support, and means for driving the truck wheels to propel the apparatus bodily along the mine trackway to effect rectilinear sumping and withdrawal movements of said kerf cutter.
149. In a mining apparatus, a portable base, an arm structure pivotally mounted on the forward end of said base to swing in a vertical direction relative thereto about a horizontal axis, a cutter head rotatably mounted on the outer extremity of said arm structure and a kerf cutter pivotally mounted on said cutter head for swinging movement relative thereto about an axis at right angles to the head axis, and means for propelling said base bodily toward and from the coal face to effect rectilinear sumping and withdrawal movements of said kerf cutter.
150. In a mining apparatus, a portable base, an arm structure pivotally mounted on the forward end of said base to swing in a vertical direction relative thereto about a horizontal axis, a support rotatably mounted on the outer extremity of said arm structure, a cutter support rotatably

mounted on said first support, a kerf cutter carried by said second support, and means for propelling said base bodily toward and from the coal face to effect rectilinear sumping and withdrawal movements of said kerf cutter.

151. In a mining apparatus, a portable base, supporting means in the form of an arm structure pivotally mounted on said base to swing in a vertical direction relative thereto about a horizontal axis extending transversely of said base, an arm structure pivotally mounted on the forward extremity of said supporting means to swing in a vertical direction relative thereto about a horizontal axis, a cutter head rotatably mounted on the outer extremity of said arm.

structure, and a kerf cutter pivotally mounted on said cutter head to swing relative thereto about an axis at right angles to the head axis.

152. In a mining machine, a frame, a kerf cutter pivotally mounted thereon, a motor on said frame, mechanism driven by said motor for driving said kerf cutter including a kerf cutter driving element, a shaft driven by said driving element, and mechanism for swinging said kerf cutter relative to said frame at different speeds in opposite directions including a reversing mechanism and plural speed gearing driven by said shaft.

CERTIFICATE OF CORRECTION.

Patent No. 1,979,266.

November 6, 1934.

MORRIS P. HOLMES.

It is hereby certified that error appears in the printed specification of the above numbered patent requiring correction as follows: Page 6, line 150, claim 2, for "connecting" read connection; page 7, line 28, claim 5, for "alternately" read alternatively; and line 34, claim 6, for "opposite" read opposite; page 10, line 35, claim 47, after "loading" insert a comma; page 12, line 70, claim 76, for "machanism" read mechanism; page 13, line 95, claim 89, for "pivtotally" read pivotally; and line 96, for "or" read on; page 18, line 89, claim 136, for "foreward" read forward; and that the said Letters Patent should be read with these corrections therein that the same may conform to the record of the case in the Patent Office.

Signed and sealed this 19th day of February, A. D. 1935.

Leslie Frazer

(Seal)

Acting Commissioner of Patents.
